UNITED STATES PATENT OFFICE.

CLARENCE L. JOHNSTON AND HORACE P. BROWN, OF OAKLAND, CALIFORNIA.

INTERLEAVED PAPER ARTICLES.

1,141,395.

Specification of Letters Patent. Patented June 1, 1915.

Application filed December 1, 1913. Serial No. 803,912.

To all whom it may concern:

Be it known that we, CLARENCE L. JOHNSTON and HORACE P. BROWN, citizens of the United States, residing at Oakland, in the county of Alameda and State of California, have invented new and useful Improvements in Interleaved Paper Articles, of which the following is a specification.

This invention relates to inter-leaved sheets, and pertains especially to paper towels, toilet paper and the like.

The primary object of the invention is to so fold and inter-leaf paper sheets, whereby such sheets, even when made of the flimsiest and softest quality of paper, when grasped by a wet hand, will not be torn when drawn from the holder.

In the demand for things sanitary, a large market has developed for individual paper towels and the problem has been first, to arrange the towels so that they may be withdrawn singly, and second, to insure against their being torn by the wet hands.

The invention consists of the parts and the combination and construction of parts as hereinafter more fully described and claimed, having reference to the accompanying drawings, in which—

Figure 1 is a vertical, longitudinal section illustrating the folded towels. Fig. 2 is a plan view of a towel unfolded. Fig. 3 is a detail perspective showing folded towels.

A represents a paper towel according to our invention; each individual towel consisting of a single sheet of paper of suitable absorptive material.

The construction of the towels, as well as the method of arrangement for dispensing the towels, are the features of the present invention.

Each sheet A is folded adjacent to its center, as shown at 2, so that the sheet is divided into two portions of unequal length 3 and 4. The longer section 3 being the section of greater area is folded in an opposite direction to the section 4 along the transverse line 5, near its outer end, so as to provide a short end edge fold 6. The length of this short folded section 6 is such that its edge 7, which is exposed, is approximately coincident with the edge 8 of the under folded section 4; in other words, the length of the narrow folded portion 6, measured on the line of the length of the folded sheet,

plus the length of the under folded section 55 4 approximately equals the length of that portion of the top section 3 between the lines 2—5. When a sheet has thus been folded the three sections 4—3—6 are in relative zig-zag formation; that is, the section 6 and section 4 are folded in opposite directions on section 3.

Assuming that each leaf A is folded in the manner described, then each sheet is interlocked with the next adjacent sheet so 65 that all of the sheets are connected by each being folded alternately over or with a half of the succeeding sheet. In actual practice this interleaving is done by machinery, not necessary here to be shown but forming the 70 subject-matter of a separate application, whereby the leaves are turned from two continuous rolls of paper and cut alternately and interfolded in the manner before described; the double folded section 3 of one 75 sheet being adjacent to the section 4 of an immediately succeeding sheet, so that the edge 8 of the latter sheet is really a continuation of the edge 7 of the next adjacent sheet. 80

One important feature of this invention is the fact that these individual sheets A are made from a practically continuous web, which web in its manufacture has its grain of greatest strength running lengthwise of the web. That is, in our paper towel the grain is lengthwise of the towel and the folds 2—5 are both crosswise of the grain, thus making a much stronger paper towel than would be made by having the folds run 90 lengthwise of the grain. When the sheets are so folded and interleaved they are placed in a container, as B, which container has a slot C through which a section 3 of the outermost sheet may project with the narrow fold 6 exposed to view. When a person desires a sheet, the folded portion 6 is grasped by the fingers and a sheet pulled out. The act of pulling out one sheet exposes the next succeeding sheet with its fold 100 6 in readiness for the next operation.

As the hands of the user are usually wet, it has been found that, with towels folded lengthwise of the grain, the portion of the paper grasped by the wet hands would give 105 way without allowing a towel to be withdrawn. It is for this reason that we have designed a paper towel with the grain run-

ning lengthwise of the sheet and have further reinforced the towel by overturning a short finger-hold section, as 6, with the result that a practically successful paper 5 towel is produced.

The dispenser B here shown is simply for the purpose of illustrating the method of use.

The foregoing arrangement provides a 10 continuous package suitable for various uses where individual sheets of light, flimsy material are to be dispensed.

Having thus described our invention, what 15 we claim and desire to secure by Letters Patent is—

1. A stack of leaves for use in a slotted container consisting of a series of sheets, each sheet being folded into an under long part and a top short part, the free end of the 20 long part being folded over to form a relatively narrow hand gripping flap of double thickness, said sheets being arranged so that the flaps of the sheets are engaged between and directly with the under and 25 top parts of an adjacent sheet and at the central line of fold of the sheet whereby when a lower sheet is pulled out of the container slot same will draw the hand gripping flap of the next sheet through the slot 30 and then will disengage itself from said ad-

jacent sheet without completely pulling the latter through the slot.

2. A paper stack consisting of a series of U-shaped leaves one of the free ends of each of which is turned outwardly and folded 35 over to form a hand gripping part of double thickness, said sheets being disposed so that the hand gripping flaps of adjacent leaves are alternately located at opposite ends of the stack and are received in the space between and directly engaged with the parts of said adjacent leaves.

3. A paper stack consisting of a series of leaves having a lower long part provided with a hand gripping folded over flap and a 45 short upper part, said leaves being arranged so that the short upper part and the flap of two adjacent leaves extend in the same plane and at their free edges confront one another and are received between the upper and 50 lower parts of a third leaf.

In testimony whereof we have hereunto set our hands in the presence of two subscribing witnesses.

CLARENCE L. JOHNSTON.
HORACE P. BROWN.
